UNITED STATES PATENT OFFICE

JAMES J. PELOUCH, OF NEWBURGH HEIGHTS, AND PAUL I. SCHULTZ, OF CLEVELAND HEIGHTS, OHIO, ASSIGNORS TO THE UNITED STATES AIR COMPRESSOR COMPANY, OF CLEVELAND, OHIO, A CORPORATION OF OHIO

DESIGN FOR A GREASE GUN HANDLE

Application filed September 22, 1931. Serial No. 41,179. Term of patent 14 years.

To all whom it may concern:

Be it known that we, JAMES J. PELOUCH and PAUL I. SCHULTZ, citizens of the United States, residing respectively at Newburgh Heights and Cleveland Heights, in the county of Cuyahoga and State of Ohio, have invented a new, original, and ornamental Design for Grease Gun Handle, of which the following is a specification, reference being had to the accompanying drawings, forming part thereof.

In the drawings, Fig. 1 is a side elevation of the grease gun handle showing our new design; Fig. 2 is a perspective view thereof.

The dominant feature of the handle is the

provision of a relatively narrow attaching bar intermediate the ends of the handle. This enables the index finger to be positioned above the bar and the remaining fingers below the bar when the handle is gripped whereby the center of the work is approximately in line with the center of the wrist, and whereby none of the fingers are pinched, while the gun is being used.

We claim:

The ornamental design for a grease gun handle substantially as shown and described.

JAMES J. PELOUCH.
PAUL I. SCHULTZ.
